UNITED STATES PATENT OFFICE.

JOHN BILSBOROUGH, OF BRISTOL, RHODE ISLAND, ASSIGNOR OF ONE-HALF
TO JOSEPH ALBERT PRESCOTT, OF FOXBOROUGH, MASSACHUSETTS.

SADDLE FOR TOP ROLLS.

SPECIFICATION forming part of Letters Patent No. 650,776, dated May 29, 1900.

Application filed December 17, 1898. Serial No. 699,554. (No model.)

To all whom it may concern:

Be it known that I, JOHN BILSBOROUGH, of Bristol, in the county of Bristol and State of Rhode Island, have invented certain new and useful Improvements in Saddles for Top Rolls, of which the following is a description sufficiently full, clear, and exact to enable those skilled in the art to which it appertains or with which it is most nearly connected to make and use the same.

This invention has relation to so-called "saddles" for top rolls of fiber-treating machines—for example, spinning-machines—the saddles being means coöperating with weighted stirrups hung thereon for holding the top rolls down upon the roving with the requisite degree of tension. The saddles bear upon the journals of the rolls, which have suitable bearings in the roller-stands. Between the journals there are enlarged leather or other similarly-covered parts which constitute the working parts of the rolls, and which parts to perform their functions efficiently must be kept clean.

It is necessary to the accomplishment of the best results from the use of top rolls and to secure the ends of economy that the journals of the rolls should be well and uniformly lubricated, and in order that this may be done it has heretofore been common to place a wick consisting of suitable yarns or fibers in a recess formed in the upper side of the back saddle and "thread" the ends of the wick through holes leading to the points where the saddles bear upon the journals of the rolls. With this construction and arrangement two or three material difficulties arise. First, inasmuch as when the machine is being cleaned (which is frequently necessary) in wiping off and picking out dust and "flyings" there is great liability of having the lubricating-wicks picked out and wiped away as dirt, and when this was done the mischief had to be repaired at the cost of time, of experienced help, and new material. Second, as the lubricant was dropped upon the wick on top of the saddle it was frequently, through almost innumerable causes, transferred to the surface of the rolls, and by that means the serviceability of the latter was seriously impaired. Again,

other trouble of perhaps less importance occurred.

It is the purpose of this invention to remedy the mischiefs and troubles mentioned, making it convenient incidentally to provide other improvements of more than mere mentionable importance.

This invention consists, rudimentarily, in providing back saddles of top rolls with lubricating-wicks having their main or body portion concealed within the saddles, so that they are not only substantially out of sight, but so protected that they cannot be accidentally picked out or wiped away in cleaning the machine and forming a hole in the saddle to convey a lubricant to the intermediate portion of the body of the wick, so that the lubricant may be the better preserved against waste and permitted to be evenly and steadily conveyed to the bearing-surfaces of the journals of the rolls and also so that the lubricant may not be so liable to get out on the working surfaces of the rolls, all as set forth in the appended claims.

Reference is to be had to the annexed drawings, and to the letters marked thereon, forming a part of this specification, the same letters designating the same parts or features, as the case may be, wherever they occur.

Of the drawings, Figure 1 is a vertical longitudinal central sectional view of top-roll saddles shown in connection with top rolls and a stirrup and illustrating my invention in connection therewith. Fig. 2 is a similar sectional view, but showing a slightly-modified form of the upper forward saddle. Fig. 3 is plan view of the upper forward saddle shown in Fig. 1. Fig. 4 is a similar view of the same saddle as represented in Fig. 2. Fig. 5 is a plan view of the bottom or rear saddle. Fig. 6 is a cross-sectional view taken on the line 6-6 of Fig. 5.

In the drawings, *a* designates the upper or forward saddle, and *b* the rear saddle, the latter adapted at its forward and rear ends to bear upon the journals *c c* of the drawing-rolls and the former saddle at its forward end to bear upon the journal *d* of the upper drawing-rolls and at its rearward end upon the back or upper side of the saddle *b*, as is usual.

in the construction and arrangement of saddles, excepting as is hereinafter described as novel and peculiar.

5 *e* designates the stirrup, arranged, as usual, to engage the saddle *a* and adapted at its lower end to receive the commonly-employed weighted lever.

Instead of forming chambers in the upper surfaces of the back saddle *b* and placing wicks in said chambers, as has heretofore been commonly done, in order to take up a lubricant and convey the same to the journals of the top rolls I form a hole or aperture through the body of the saddle and thread or draw the

15 lubricant-conveying wick through said aperture, so that it shall not only be substantially concealed from view, but be protected against dust or flyings lodging therein to absorb the lubricant and befoul the parts and also so as

20 to be protected against accidental removal or against being accidentally picked out in cleaning the machine. This is the essential part of my invention—that is, that I provide the body of the back saddle *b* with an aperture *b'*, extending longitudinally through it, so that the oil-conveying wick *n* may be protected from end to end against accidental displacement or against being wiped off or picked out in cleaning the machine, and all this notwithstanding the fact that at the ends of the wick, as at *g g'*, they are made to project from the aperture to a slight extent into cavities *m m'* and also notwithstanding the fact that oil-holes are provided at some points, so that a

30 lubricant poured into said holes may reach the body of the wicks intermediate of their ends and be taken up thereby to be conveyed in a regular and proper manner to the journals of the rolls.

35 In Fig. 6 I have shown the hole or aperture *f*, in which the wick is drawn, as kite or balloon shaped. This form, for several reasons, I may in some instances prefer to use, though I desire it to be expressly understood that my

40 invention, in its broad sense, comprehends a back saddle in which the lubricant-supplying wick is contained within a hole or aperture bored or formed through the body of the back saddle, so that the wick is not exposed to an

45 extent rendering it liable to be picked out by mistake or wiped off or to have the lubricant contained therein liable of being conveyed to the surface of the top roll and a hole or aperture formed in the saddle for conveying a lubricant to the body of the wick at a point intermediate of its ends.

50 By my invention in addition to the advantages before mentioned I have ascertained that the lubricant absorbed by the wick is

55 more evenly conveyed to the roller-journals, and, furthermore, the lubricant lasts longer by reason of the fact that it is not wasted by being wiped off with dirt or conveyed too rapidly to the journals. Again, by my invention, inasmuch as the wick is not exposed on the up-

per sides of the saddles excepting to a slight extent, as the end may project through the aperture formed in the body of the saddle, as shown, there is little or no liability of dragging or conveying the lubricant from the wick to the outer working surfaces *k* of the rollers, as is the case with back top-roll saddles as now commonly employed, it being well understood that if oil or other similar lubricant gets upon the surface of the rolls it interferes to a very serious degree with the serviceability of the latter, if it does not entirely destroy the same.

55 It is to be noted that the wick hole or bore extends through the body of the back saddle between the inner end walls of the cavities formed at the extremities of the saddle in the under side of the same. This is of obvious advantage both in the manufacture of the saddle and in the threading of the wick therethrough.

60 In Figs. 1 and 3 I have shown the forward saddle *a* as being capable of receiving a lubricant to be conveyed to the wick through the medium of a chamber *h* back of the stirrup *e*, while in Figs. 2 and 4 I have formed a chamber *i* in front of the stirrup *e* and, as is represented in Fig. 5, I form a recess or chamber *j* in the upper side of the saddle *b*, with oil-holes *j'* in the bottom of said chamber communicating with the wick in order to convey a lubricant to the latter. I however make no claim herein to the forward saddle or its structural characteristics.

65 Having thus explained the nature of the invention and described a way of constructing and using the same, though without attempting to set forth all of the forms in which it may be made or all of the modes of its use, it is declared that what is claimed is—

70 1. A back top-roll saddle provided with a hole or aperture extending longitudinally through its body part and opening at opposite ends into cavities at points in proximity to the bearings of the rollers upon which the saddle rests, and one or more oil-holes entering from above into the said longitudinal aperture intermediate the ends thereof, together with a wick occupying the longitudinal aperture and protruding from the ends thereof.

75 2. A back top-roll saddle having cavities in its under side at opposite ends and a longitudinal bore extending through the body of the saddle between the inner end walls of the cavities; together with a wick occupying said bore with its ends protruding into the cavities, substantially as described.

80 In testimony whereof I have signed my name to this specification, in the presence of two subscribing witnesses, this 5th day of October, A. D. 1898.

JOHN BILSBOROUGH.
